DESIGN FOR AN ATOMIZER

George Grunberg, New York, N. Y.

Application November 22, 1939, Serial No. 88,413

Term of patent 7 years

To all whom it may concern:

Be it known that I, George Grunberg, a citizen of the United States of America, residing in the Borough of Manhattan, in the city, county, and State of New York, have invented a new, original, and ornamental Design for an Atomizer, of which the following is a specification, reference being had to the accompanying drawing, forming part thereof, wherein:

Figure 1 is a front elevational view of an atomizer embodying my new design.

Fig. 2 is a side elevational view of the atomizer shown in Fig. 1 as viewed from the left thereof.

The dominant features of my design reside in the portions shown in full lines.

I claim:

The ornamental design for an atomizer, as shown and described.

GEORGE GRUNBERG.
